UNITED STATES PATENT OFFICE

136,527

DESIGN FOR AN AUTOMOBILE VENTILATOR INSECT SCREEN

Joseph C. Mullner, St. Paul, Minn., assignor of
one-half to Ludwig Mullner, St. Paul, Minn.

Application August 31, 1942, Serial No. 108,085

Term of patent 14 years

To all whom it may concern:

Be it known that I, Joseph C. Mullner, a citizen of the United States, residing at St. Paul, in the county of Ramsey and State of Minnesota, have invented a new, original, and ornamental Design for Automobile Ventilator Insect Screen, of which the following is a specification, reference being had to the accompanying drawing, forming part thereof.

Figure 1 is a rear perspective view of an auto-

mobile ventilator insect screen showing my new design;

Figure 2 is a side elevational view of the same;

Figure 3 is a rear elevational view of the same;
and

Figure 4 is a top plan view of the same.

I claim:

The ornamental design for an automobile ventilator insect screen, as shown.

JOSEPH C. MULLNER.
